UNITED STATES PATENT OFFICE.

FRANK A. ROBITAILLE, OF RIMINI, MONTANA.

HOIST.

SPECIFICATION forming part of Letters Patent No. 425,699, dated April 15, 1890.

Application filed January 11, 1890. Serial No. 336,665. (No model.)

To all whom it may concern:

Be it known that I, FRANK A. ROBITAILLE, of Rimini, in the county of Lewis and Clarke and State of Montana, have invented a new and Improved Hoist, of which the following is a full, clear, and exact description.

My invention relates to improvements in hoisting apparatus; and the object of my invention is to provide a simple, efficient, light-
10 running, strong, and durable hoisting apparatus that is especially adapted to raise material from a mine-shaft, but that may be used for all kinds of hoisting purposes.

To this end my invention consists in certain features of construction and combinations of parts, that will be hereinafter fully described, and specifically pointed out in the claims.

Reference is to be had to the accompanying drawings, forming a part of this specification, 20 in which similar letters and numerals of reference indicate corresponding parts in all the figures.

Figure 1 is a side elevation of the device as applied to a bucket or cage in a shaft; Fig. 2, 25 a plan view of the frame containing the winding-drum and driving mechanism; Fig. 3, an end view of the same, and Fig. 4 a front elevation of the same.

The upright standards A at the corners, 30 the side bars B C and B' C', attached thereto, and the cross-bars D at the top constitute the frame of the driving and winding machine. The side bars B, B', C, and C' pass through mortises in the standards A. The bars B, B', and C are held in position therein by keys a, which also take up any wear there may be in the joints of the frame. The bar C' is pivoted at one end by the bolt b in one of the standards, and the other end is 35 capable of a limited vertical movement in the opposite standard. The bars B' and C' extend at one end beyond the standards A. The cross-bars D extend across the top of the frame and are bolted at each end to the side bars B B'. The side bars B, B', C, and C' are provided with bolts 1, which pass through the ends thereof, and the standards A are prevented from spreading apart by rods d, which pass through the standards on each 45 end of the machine and are provided at each

end with suitable nuts to hold them in position.

I have shown the frame attached to the beams E of a mill, which in turn rest upon the timbers F, which support a counter-shaft 55 e; but it is obvious that the timbers F may be attached to the machine-frame and the shaft e mounted thereon. The shaft e is mounted in suitable boxes f upon the timbers F, and is provided with a driving-pulley 60 H and a friction-pulley J, which is attached to the shaft near the inner end thereof, and which is made, preferably, of paper.

Directly above the pulley J is a pulley K, which has a face of about the same width as 65 the face of the pulley J, but which is of much larger diameter. The pulley K is attached to the shaft L, which extends across the frame of the machine and turns in suitable bearings 70 3, which are attached to the side bars C and C' by the bolts 4, the pulley K being upon the end of the shaft next the side bar C', so that the pulley may be easily raised with said side bar.

The shaft L is also provided with a drum M, 75 which is attached thereto, is provided with flanges M' at each end, and is held in position upon the shaft by a collar g. A vertical lever-arm N is pivoted near the center by a pin h to the projecting end of the side bar B' 80 above the bar C', the lever being mortised to receive the bar B'. The ends of the lever-arm N are slotted, and the lower end straddles the end of the bar C', and is pivoted thereto by the bolt i', which extends through 85 a diagonal slot j in the bar C', which bolt may be provided with a roller, as i, to travel in said slot, so that when the lever-arm N is moved forward or backward the bolt i' will move in the inclined slot j and the bar C' 90 will be raised or lowered. The upper end of the lever N is pivotally attached to the connecting-rod O' by the pin l, and the connecting-rod is attached to the rod or pipe O by the bolt l'; but the end of the rod or pipe O may 95 be flattened and pivoted directly to the lever N, and the apparatus will work as well. The rod O extends to the mouth of the shaft P, where it is attached to the lever R by the pin m.

The lever R is pivoted at the bottom to the 100

lower part of the frame S, and is provided with a suitable latch n, which may engage a notch p of the rack, which is also attached to the frame S, and hold the lever R in a desired position.

- 5 Attached to the drum M is a rope t, which passes over a pulley u, that is hung in the top of the frame S, and is attached to the bucket or cage T in the shaft P, so that when 10 the rope is wound upon the drum M the bucket T will be raised and when it is unwound the bucket will be lowered.

A curved brake-shoe W is attached by bolts 2 to the under side of the cross-bars D just 15 above the pulley K, so that by raising the pulley against the brake-shoe it may be stopped entirely, or its speed may be slackened when the bucket T is lowered into the shaft P and the rope t is unwound from the drum, thus 20 turning the drum, the shaft L, and the pulley K.

The device is operated as follows: The operator at the mouth of the shaft P grasps the lever R and throws it forward. This brings 25 forward the rod or pipe O and the upper end of the lever-arm N, causing said lever-arm to tilt on the pin h, thus throwing out the lower end of the arm, forcing the bolt i' into the upper end of the inclined slot j, depressing 30 the side bar C', and forcing the pulley K, which is mounted thereon, upon the pulley J, and as the pulley J is in constant motion the friction of the two pulleys will transmit the motion to the pulley K, which will turn the 35 shaft L, to which it is attached, the drum M upon said shaft, and will wind the rope t upon said drum, thus raising the bucket T at the other end of the rope. To lower the bucket T, the lever R is thrown in the opposite direction, thus actuating the rod O and lever-arm N and throwing the bolt i' into the lower 40 end of the slot j, raising the side bar C' and pulley K from the pulley J. The weight of the bucket will then carry it down and unwind the rope t from the drum M. If the 45 bucket travels too fast, the lever R may be thrown still farther in the same direction, thus forcing the bolt i' farther into the lower end of the slot j and raising the side bar C' 50 till the top of the pulley K bears against the brake-shoe W, thus slackening the speed of the pulley and of the drum M, which is attached to the same shaft as the pulley, or stopping it altogether. The speed with which

the bucket or cage descends may thus be regulated by the pressure upon the lever R.

It will be seen from the foregoing description that by connecting the device with a revolving shaft of a mill or other power the whole apparatus may be operated and controlled by one person at the mouth of the shaft.

Having thus described my invention, what I claim as new, and desire to secure by Letters Patent, is—

1. A hoisting apparatus consisting, essentially, of a suitable frame having a pivoted side bar, a power-shaft provided with a friction-pulley, a second shaft journaled in a fixed bar and the pivoted side bar of the frame and 70 provided with a friction-pulley and a winding-drum, and a lever pivoted on the frame and provided with a pin engaging a slot in the pivoted side bar of the frame, substantially as shown and described.

2. In a hoisting apparatus, the combination, with a frame having one side bar extended and a corresponding lower side bar pivoted at one end and also extended at its free end, which free end is provided with a diagonal 80 slot, and a power-shaft provided with a friction-pulley, of a second shaft provided with a winding-drum and a friction-pulley, said shaft being journaled at the end carrying the friction-pulley on the pivoted side bar, a 85 lever pivoted on the upper extended side bar, and a pin in the lower end of said lever engaging the slot of the pivoted bar, substantially as described.

3. In a hoisting device, the combination, 90 with a frame having the extended side bar B' and pivoted side bar C', having a diagonal slot in its free end, and a power-shaft provided with a friction-pulley, of shaft L, friction-pulley K, lever N, and pin i', substantially as 95 shown and described.

4. In a hoisting device, the combination, with a frame having extended side bar B' and pivoted side bar C', having a diagonal 100 slot in its free end, and a power-shaft provided with friction-pulley J, of shaft L, lever N, pin i', and brake-shoe W, substantially as shown and described.

FRANK A. ROBITAILLE.
